(57) **CLAIM**

The ornamental design for a waste container stabilizer, as shown and described.

DESCRIPTION

FIG. 1 is a perspective view of a waste container stabilizer showing the new design, with an exemplary waste container depicted in broken lines;

FIG. 2 is a top plan view the waste container stabilizer of FIG. 1, depicting the circular ring shape of the stabilizer; FIG. 3 is a bottom plan view thereof;

FIG. 4 is a side view thereof, wherein one of the three legs is hidden behind the leg on the leftmost side of FIG. 4; and, FIG. 5 is a side view thereof, wherein all three legs are depicted.

The broken lines in the figures are for illustrative purposes only and do not form a part of the claimed design.
